CLAIM

The ornamental design for a terminal fitting as shown and described.

DESCRIPTION

FIG. 1 is a top, front and right side perspective view of a terminal fitting showing my new design;

FIG. 2 is a top, rear and left side perspective view thereof;

FIG. 3 is a front view thereof;

FIG. 4 is a rear view thereof;

FIG. 5 is a top plan view thereof;

FIG. 6 is a bottom plan view thereof;

FIG. 7 is a left side view thereof;

FIG. 8 is a right side view thereof; and,

FIG. 9 is an end view taken along the 9-9 line of FIG. 3.

1 Claim, 9 Drawing Sheets
